Primary Examiner—Ruth McInroy*Attorney, Agent, or Firm*—A. Burgess Lowe; Bruce P. Watson[57] **CLAIM**

The ornamental design for a front medial portion of a vacuum cleaner nozzle, as shown and described.

DESCRIPTION

FIG. 1 is a perspective view of a front medial portion of a vacuum cleaner nozzle showing our new design;

FIG. 2 is a top plan view thereof; and,

FIG. 3 is a front elevational view thereof.

The details shown in broken lines are shown for illustrative purposes only and form no part of the claimed design.
